CLAIM

The ornamental design for a wheel for automobile as shown and described.

DESCRIPTION

FIG. 1 is a perspective view of the subject design as viewed from the front.

FIG. 2 is a front view of the subject design.

FIG. 3 is a rear view of the subject design.

FIG. 4 is a left side view of the subject design.

FIG. 5 is a right side view of the subject design.

FIG. 6 is a top view of the subject design; and,

FIG. 7 is a bottom view of the subject design.

The broken lines in the drawings illustrate portions of the wheel for automobile that form no part of the claimed design.

1 Claim, 7 Drawing Sheets
